UNITED STATES PATENT OFFICE.

HARRY K. FAIRALL AND HOWARD L. FAIRALL, OF HIGHLAND, CALIFORNIA.

HINGE.

No. 902,808.

Specification of Letters Patent.

Patented Nov. 3, 1908.

Application filed May 29, 1908. Serial No. 435,816.

To all whom it may concern:

Be it known that we, HARRY K. FAIRALL and HOWARD L. FAIRALL, citizens of the United States, residing at Highland, in the 5 county of San Bernardino, State of California, have invented certain new and useful Improvements in Hinges; and we do hereby declare the following to be a full, clear, and exact description of the invention, such as 10 will enable others skilled in the art to which it appertains to make and use the same.

The invention relates to a hinge and more particularly to the class of hinges adapted for doors, gates or the like whereby the latter upon opening thereof may be automatically brought to a closed position.

The primary object of the invention is the provision of a hinge or hinges each comprising a strip of material bent on itself to 20 form a spiral intermediate portion terminating in securing ears and which spiral intermediate portion is traversed by a slotted member or arm forming the other portion or half of the hinge so that when the 25 door or gate is swung to an open position the same will rise by the movement of the said other hinge section upon the spiral and upon the release of the door the same will be automatically shut. With this and other objects in view the invention consists in the construction, combination and arrangement 30 of parts as will be hereinafter more fully described and as will be illustrated in the accompanying drawings which disclose the preferred embodiment of the invention, however changes, variations and modifications 35 may be made as come properly within the scope of the claims hereunto appended without departing from the spirit of the invention.

In the drawings:—Figure 1 is an elevation of a door with the hinges secured thereto. Fig. 2 is a plan view of a door in an open position with the invention applied 45 thereto. Fig. 3 is a perspective view of one hinge section which latter is adapted to be carried by the door.

Similar reference characters indicate corresponding parts throughout the several 50 views in the drawings.

In the drawings, the numeral 5 designates the door proper and 6 the side of the frame

of said door. Near the upper and lower end extremities of the door near one side edge thereof are members 7 each forming one 55 section of a hinge and includes outwardly diverging extensions 8 terminating in an arm 9 having opposed flattened faces 10 and extending at a slight angle outwardly with respect to the parallel plane of the extensions 8, and which arm has an elongated straight slot 11 engaging a spiral 12 formed of a twisted strip of material 13 which latter is bent on itself at opposite terminals of the spiral to form offsets or right angularly 65 disposed extensions 14 which latter terminate in securing extremities 15 each of which are arranged in the same plane and are secured by fasteners 16 to the frame 6 of the door. This strip of material forms 70 the other hinge section and is adapted to automatically close the door 5 when in an open position.

In each of the extensions 8 are fasteners 17 to secure the same to the door 5. It is 75 of course understood that two of these members 7 are used and also two of the strips 13 for hingedly mounting a door in its frame and which are positioned near opposite extremities thereof.

It will be obvious that when the door is 80 swung open the slotted arms 9 will traverse the spiral portions 12 of the strips 13 in an upward direction and thereby raising the door as well as bringing the same to an 85 open position. As soon as the door is released the weight thereof will cause the slotted arms of the members 7 to travel downward upon the spiral portions of the strips carried by the frame of the door and thereby 90 automatically swinging the door to its closed position. In this construction of hinge it does away with the necessity of springs to automatically close a door as the spiral portion of a hinge causes the shutting of said 95 door.

What is claimed is—

1. A hinge comprising a strip of material twisted to form a spiral portion terminating at opposite ends in offset securing extremities and a member having securing extensions and a slotted arm engaging the spiral portion of the strip. 100

2. A hinge comprising a member formed

with outwardly diverging securing extensions and an outwardly inclined angularly disposed arm containing an elongated slot and a strip of material twisted to form a spiral portion engaging the slot and traversed by said arm, said strip of material bent at opposite extremities of the spiral to form offset securing extremities.

In testimony whereof, we affix our signatures in presence of two witnesses.

HARRY K. FAIRALL.
HOWARD L. FAIRALL.
